(57) **CLAIM**

The ornamental design for a yoyo string loop display window for a package, as shown and described.

DESCRIPTION

FIG. 1 is a perspective view of a first embodiment of a yoyo string loop display window for a package;
FIG. 2 is a front elevational view thereof;
FIG. 3 is a rear elevational view thereof;
FIG. 4 is a side elevational view thereof;
FIG. 5 is another side elevational view thereof;
FIG. 6 is a top elevational view thereof; and
FIG. 7 is a bottom elevational view thereof;
FIG. 8 is a front elevation view of a second embodiment of a yoyo string loop display window for a package; and,
FIG. 9 is a front elevation view of a third embodiment of a yoyo string loop display window for a package.
The broken lines shown in FIGS. 1-9 represent unclaimed subject matter and form no part of the claimed design.
